HENRY B. HASTAD, OF BROOKLYN, NEW YORK.

MIXING DEVICE FOR INTERNAL-COMBUSTION ENGINES.

1,279,338.

Specification of Letters Patent. Patented Sept. 17, 1918.

Application filed June 26, 1917. Serial No. 177,036.

To all whom it may concern:

Be it known that I, HENRY B. HASTAD, a citizen of United States of America, residing at Brooklyn, in the county of Kings and State of New York, have invented new and useful Improvements in Mixing Devices for Internal-Combustion Engines, of which the following is a specification.

This invention relates to internal combustion engines, and more especially to mixers forming part of the charge forming devices; and the object of the same is to produce an improved mixer for insertion in the upright stretch of the intake manifold pipe whereby the vaporized gasolene and air may be more thoroughly mixed or commingled in their passage from the carbureter to the cylinders, without materially or appreciably impeding such passage.

This object is carried out by enlarging the capacity or bore of the manifold where the mixer occurs, and utilizing a specific form of mixing device in duplicate—all as hereinafter more fully described and claimed, and as shown in the drawings wherein:—

Figure 1 is an elevation of the side of an automobile engine, showing the same, the manifold and the carbureter, in diagram, and illustrating my invention in vertical section.

Figs. 2 and 3 are details of different sizes of flanges as referred to hereinafter.

My invention contemplates no change in the carbureter C, the engine E, or the manifold M, the latter in the present instance being shown as having four branches for a four-cylinder engine as usual, and the manifold being connected with the carbureter by an upright stretch of pipe as indicated at P. In this pipe I propose to insert my mixer, and the first and primary essential is that the capacity of the mixer shall be larger than that of the pipe. If the latter be what is known as a one-inch pipe, the piping in the mixer should be one and one-quarter inch or perhaps $1\frac{1}{2}$ inch, or in any event it should have from sixty to seventy-five per cent. more internal area than the upright pipe P which usually connects the carbureter with the manifold. Attached to the upper end of the pipe P is a flange 1 (see Fig. 3) having a series of apertures 2 for bolts or screws 3. Superposed upon this pipe is a short nipple 4 of larger diameter as seen, and the lower end of this nipple car-

ries a flange 5 whose bore is substantially that of the nipple, this flange also having apertures 2. At the upper end of the nipple 4 is another flange 5. Above this nipple is a second nipple 6 having a lower flange 5 bolted to that at the upper end of the nipple 4, and having an upper flange 5'. The latter is bolted to a second flange 1' whose bore is again reduced so that it is of the same size as the upper portion P' of the pipe, which latter extends thence into the branch and manifold M.

The numeral 10 designates a strainer, and the numeral 11 another similar strainer. These are preferably of brass wire mesh, made of quite fine wire and with equally fine openings, and by preference the aggregate of the openings is the same as the aggregate of the wires, or in other words the screen is fifty per cent. open. Each screen is conical as shown, with its point upward, and its length along its axis is about twice its diameter across its base. Said base is provided with a radial flange 12 which is clamped between the two flanges of the pipe system above described. That is to say, the flange of the lower screen is clamped between the flange 5 at the lower end of the nipple 4 and the flange 1 at the upper end of the pipe P, whereas the flange of the upper screen is clamped between two flanges at the lower end of the nipple 6. Instead of bolts 3 screws or other fastening devices might be used. The parts are entirely of metal, and any appropriate metal may be employed, although by preference I would use brass. The device may be made and applied at the time the machine is constructed, or the pipe leading from the carbureter to the manifold may be cut and the device inserted into a machine already set up. I do not confine myself to any particular type of carbureter or manifold, and the engine may have as many cylinders as desired; but I prefer that this mixing device shall be inserted in an upright portion of the inlet manifold. I have shown no packing between the flanges which are connected by bolts, either above or below the flanges at the lower ends of the conical screens, but it is quite possible that gaskets might be employed to absolutely seal the device against leak.

A mixer of this kind interposed in an uninterrupted upright stretch of the inlet manifold possesses many advantages. First, it will almost positively prevent back-firing

from any cylinder to the carbureter, because flames will not pass through so fine a screen. Next, it acts as a very thorough mixer for the charge flowing through the pipe, reliably breaking up any globules of the gasoline which said charge may contain. Even if the mixture is so rich that globules form after it has passed through the first screen, they are broken up by the second screen. 10 Next, the conical shape of the screens is adopted to purposely draw the charge away from the walls of the pipe, to which I find it has a tendency to cling and upon which it will to a greater or less extent condense. 15 The charge flowing through the pipe P is under considerable speed, owing to the suction set up in the cylinders, and the insertion of any screen, baffle, or other interruption within such pipe naturally retards such speed; therefore I have enlarged that portion of the pipe where my mixer occurs, as by using nipples 4 and 6, and couplings or flanges 5 whose bores are larger than that of the pipes P or P', so that the retarding 20 effect is overcome or offset. Finally, I might say theoretically that the rapidly moving charge issuing from the pipe P flows along the axis of the lower strainer 10 and through the mesh thereof near its apex, 25 therefore setting up a suction in the annular space around the smaller end of this strainer, which suction draws much of the mixture through the mesh at the base of the cone. Beyond the point of this cone there 30 may be said to be a jet of mixture flowing along the axis of the entire device and projected into the base of the upper cone 11 and along its axis; but that part of the mixture which was drawn through the base 35 of the first cone and surrounds its smaller end now flows along within the nipple 4 in waves which are given a swirling or rolling action so that they enter the base of the upper cone at perhaps less speed than said 40 jet which is projected into this cone from the apex of the lower cone. The upper cone now repeats the action to an extent, excepting that said waves are drawn through the walls of this upper cone with greater ease than the charge was initially drawn through the walls of the lower cone, because at that time it was under greater speed in the pipe section P. Outside the smaller portion of the upper cone the now thoroughly mixed charge unites within the upper end of the upper nipple 6, and passes through the coupling or flange into the pipe section P' and on through the manifold. What retarding effect was produced by the interposition or insertion of the two cones has been offset by the enlargement of the passage by the insertion of nipples 4 and 6 whose bores were larger than those of the pipe sections P and P', and therefore, while the charge moved perhaps a little more slowly through the nipples than it did through the pipe sections, I consider this quite desirable. It is obvious that by removing the bolts or screws 3, access to the interior may be had at any time for inspection or repair. 70

What is claimed as new is:—

The combination with the intake pipe of an internal combustion engine, of a sectional mixer incorporated in said pipe and embodying a plurality of units each comprising a nipple having an uninterrupted cylindrical bore larger than that of the pipe, flanges connecting the nipples with each other and with the ends of the intake pipe, and a strainer for each mixer section consisting of a conical body standing within and of equal size with the bore of its nipple and having an outstanding flange at its base clamped between two of said flanges, each strainer being completely housed with- 85 in its own nipple. 75

In testimony whereof I affix my signature.
HENRY B. HASTAD.
